PAPER HANDLING MECHANISM FOR
ACCOUNTING MACHINESWalter A. Anderson, Bridgeport, Conn., assignor
to Underwood Elliott Fisher Company, New
York, N. Y., a corporation of Delaware

Application December 12, 1938, Serial No. 245,071

2 Claims. (Cl. 197—135)

This invention relates to accounting machines, and more particularly to a means for guiding and holding front fed cards that are to be printed on such machines.

5 Cards are used by many business establishments for keeping records, and it is desirable to have a means on modern accounting machines that will accommodate these cards and hold them in place during the printing operations.

10 It is, therefore, an object of the present invention to provide suitable guiding and holding means to facilitate the rapid insertion and removal of the cards, and which is adjustable to accommodate the varying lengths and widths 15 of the cards.

Another object of the invention is to make the guides sufficiently yielding to relieve the operator of having to force the cards into inserted position in the guides.

20 With these and incidental objects in view, the invention consists in certain novel features of construction and combinations of parts, the essential elements of which are set forth in appended claims, and a preferred embodiment 25 of which is hereinafter described with reference to the drawing which accompanies and forms part of the specification.

In the drawing:

30 Figure 1 is a perspective view of an accounting machine having a paper carriage embodying the present invention.

Figure 2 is a detailed right side elevation of one of the improved card guiding and holding elements showing a card fully inserted therein,

35 Figure 3 is a perspective view thereof, and

Figure 4 is a detailed perspective view of a lateral edge guide used in combination with the guides shown in Figures 2 and 3.

Carriage in general

40 The accounting machine 1 (Figure 1) is similar to that disclosed in the application Serial No. 581,800 of Oscar J. Sundstrand, filed December 18, 1931, which issued as Patent No. 2,194,270,

45 March 19, 1940. A carriage 2 of the rear feed type is mounted for movement along a track 3. As the carriage moves from right to left, it is stopped in various columnar positions so that type bars 4 on the accounting machine may print

50 on work sheets fed around the platen 5. The mechanism for tabulating the carriage from column to column and for returning it to its initial position is disclosed in Patent No. 2,194,270. The carriage is adapted to accommodate rear 55 fed paper such as a journal or ledger sheet 6,

and front fed cards such as 7. The platen may be rotated manually by knobs 8 secured to each end of the platen shaft 11, or may be rotated automatically during operations of the machine by a suitable feed pawl and ratchet wheel arrangement such as that disclosed in Patent No. 2,194,270.

Mechanism for guiding and holding front fed cards or short forms

10 Referring to Figures 1 and 2, the carriage side walls 12 have secured thereon upwardly extending arms 13 between which there is connected a square rod 14 extending across the entire carriage. Rod 14 is formed with an offset portion 15 to provide ample clearance for the operator's hand between the rear structure and rod 14 during the insertion and removal of cards 7. A stationary plate 16 extends transversely across the entire carriage and is secured at its opposite 15 ends to side walls 12, the upper edge of the plate lying just below the printing line of the platen 5. Brackets 17, having square apertures 18 (Fig. 19), are slidably mounted on rod 14 on opposite sides of offset 15, and carry thumb screws 19 25 arranged to bear against the rod to hold the brackets in adjusted position. Each bracket 17 carries a depending guide finger 20 pivoted on a rod 21 secured between the side walls of the brackets. A pair of weak springs 22, connected 30 between the upper ends of guide fingers 20 and a stationary pin 23 in each bracket 17, tensions the guide fingers counter-clockwise about rods 21, and causes inturned flanges 24, formed on the lower ends of the fingers, to bear against stationary plate 16, as shown in Figure 2. The width of flanges 24 is sufficient to hold guide fingers 20 in spaced relation from platen 5 and plate 16, whereby a chute is formed to receive cards 7, 35 guide fingers 20 forming the forward portion of the chute and platen 5, together with plate 16, forming the rear portion thereof. An adjustable bracket 25 (Figures 1 and 4) resembling bracket 17 is mounted on rod 14 to the left of the left hand guide finger 20, and has an extended left side wall 26 serving as a lateral edge 40 guide for the cards.

Insertion of cards

When a card is to be inserted in the chute, it 50 is held by the operator in the position shown in dot-and-dash lines in Figure 1, and is inserted downwardly as indicated by the dash line 27 in Figure 2 until the lower edge of the card bears against a point indicated at 28 on the guide 55

finger 20. Further downward insertion of the card causes it to follow finger 20 until its lower edge abuts flange 24, which serves as a stop. This fully inserted position is shown by dot-and-dash lines in Figure 2. It will be noted that guide finger 20 bends the card slightly to create sufficient friction to hold it in printing position.

If the resistance offered by the tendency of the card to remain flat is greater than the resistance offered by springs 22, downward pressure on the card past the point 28 causes fingers 20 to yield to permit further insertion of the card without additional pressure by the operator. Then when the lower edge of the card reaches a point along guide fingers 20 below point 28, the tension of springs 22 overcomes the resistance offered by the card, and causes the card to flex about the printing line of platen 5.

In practice, this construction has been found to greatly facilitate the quick and smooth insertion and removal of cards of varying thicknesses.

While the form of mechanism herein shown and described is admirably adapted to fulfill the objects primarily stated, it is to be understood that it is not intended to confine the invention to the one form of embodiment herein disclosed, for it is susceptible of embodiment in various forms, all coming within the scope of the claims which follow.

What is claimed is:

1. In a machine of the class described having a paper carriage, a platen mounted in said carriage, a front feed card holding means including a guide lying in front of the platen and extending from a position above the printing point to a position below the printing point, and a spring means acting on the guide and having a tension weak enough to enable the stiffness of a card, when inserted quickly, to move the guide away from the platen, and strong enough to cause the guide to move towards the platen and thereby bend the card around the platen at the printing point, after the card is inserted.

2. In a machine of the class described having a paper carriage, a platen mounted in said carriage, a front feed card holding means including a guide pivoted on the carriage at a point above the platen and extending from a position above the printing point to a position below the printing point, and a spring means connected to the guide and to a stationary part of the carriage and having a tension weak enough to enable the stiffness of a card, when inserted quickly, to move the guide away from the platen, and strong enough to cause the guide to move towards the platen and thereby bend the card around the platen at the printing point after the card is inserted.
